UNITED STATES PATENT OFFICE.

FREDERICK S. DUESENBERG AND AUGUST S. DUESENBERG, OF ELIZABETH, NEW JERSEY.

LUBRICATING SYSTEM.

1,363,501.

Specification of Letters Patent. Patented Dec. 28, 1920.

Original application filed April 14, 1913, Serial No. 760,851. Renewed June 24, 1918, Serial No. 241,689.
Divided and this application filed May 31, 1919. Serial No. 301,082.

To all whom it may concern:

Be it known that we, FREDERICK S. DUESENBERG and AUGUST S. DUESENBERG, citizens of the United States, and both residents of the city of Elizabeth, in the county of Union and State of New Jersey, have invented certain new and useful Improvements in Lubricating Systems; and we do hereby declare that the following is a full, clear, and exact 10 description of the same, reference being had to the accompanying drawings, and to the numerals of reference marked thereon, which form a part of this specification.

This application for patent constitutes a 15 division of our co-pending application for patent for internal combustion engines, filed April 14, 1913, Serial No. 760,851, renewed June 24, 1918, Serial No. 241,689.

The question of lubrication in an internal 20 combustion engine is a serious one, and oftentimes has confined the design and arrangement of the various mechanisms forming a part of the engine to an inefficient association of the parts. For the purpose of 25 properly lubricating the valves and the cylinders and the operating mechanism connecting the crank shaft of the engine therewith, said valves and mechanisms have been disposed in a certain relation to one another 30 and to the cylinders of the engine to insure correct lubrication thereof at all times. However, in the past it has been found that the general arrangement of the valves in the cylinders, in order to afford simplicity 35 of operation and perfect lubrication, has led to a construction wherein the operation is necessarily inefficient.

This invention relates to an internal combustion engine wherein the parts are designed and arranged so as to secure the utmost economy and efficiency of operation, and wherein the lubricating mechanism is 40 associated with the valve gear, the mechanisms of the gear being specially constructed 45 and incased within the engine to insure a thorough lubrication of all the parts at all times.

Excessively large clearance spaces, particularly in a T-head motor, and as well, 50 though not so great, are also found in the well known L-head type, but owing to the complications of mechanism for overcoming these features and the difficulty of lubricating the same, most designers and manufac-

turers in the past have avoided making any 55 change or radical departure therefrom.

This invention, however, relates to an internal combustion engine comprising a plurality of upright cylinders, each having a small clearance space arranged directly 60 above and co-axial with the cylinder, with the valves communicating laterally thereinto, and with mechanisms driven from the cam shaft of the engine to actuate the valves, suitable means being provided for efficiently 65 lubricating all of the working parts at all times.

It is an object of this invention to afford a construction wherein the crank case or 70 splash lubrication may be regulated externally of the engine to maintain the proper depth or amount of oil in the crank case for lubrication, dependent upon the requirements for service of the engine.

It is also an object of this invention to 75 construct an internal combustion engine wherein a sub-base is provided in the crank case affording, with the walls of the crank case, a container for a bath of oil for splash lubrication, and with mechanisms adjustable externally of the engine to control the flow of oil into a reservoir beneath said sub-base, thereby regulating the depth of oil in the bath for the splash lubrication, and the space beneath said sub-base communicating 80 with power driven force feed mechanism to 85 pump the oil through the other operating parts of the engine.

It is also an object of this invention to 90 construct an engine wherein a reservoir for lubricating oil is provided in the bottom of the crank case, and with mechanisms communicating therein to control the level of the oil in the crank case for the splash lubrication, said reservoir communicating with 95 a force feed pump which serves to pump oil to the various parts of the mechanism through tubes and pipes for the purpose.

The invention (in a preferred form) is 100 illustrated in the drawings and hereinafter more fully described.

On the drawings:

Figure 1 is an elevation of the left side of a multi-cylinder hydrocarbon engine partly broken away and in section. 105

Fig. 2 is an end elevation thereof.

Fig. 3 is a section on line 3—3, of Fig. 1.

Fig. 4 is a fragmentary sectional detail

view of the upper portion of the engine over one of the cylinders.

Fig. 5 is a fragmentary section taken longitudinally of the engine, on line 5—5, of 5 Fig. 3.

Fig. 6 is a fragmentary section taken on line 6—6 of Fig. 5.

Fig. 7 is a fragmentary section taken on line 7—7, of Fig. 5.

10 Fig. 8 is a fragmentary section on line 8—8, of Fig. 3.

Fig. 9 is a longitudinal section taken on line 9—9, of Fig. 3.

15 Fig. 10 is a fragmentary vertical section taken on line 10—10 of Fig. 1.

Fig. 11 is a fragmentary view with parts in section of the lower end of one of the rocker arms.

As shown on the drawings:

20 The crank case 1, is constructed of cast metal in any suitable manner, and is provided, if desired, with transverse interior webs, on which, and at the ends of the crank case is journaled the crank shaft 2, which

25 may be constructed, of course, as usual, the construction in this particular as to the bearings for the crank shaft, varying with the size of the engine, and the number of cylinders employed. Said crank case is provided

30 on its right side with a removable side plate 3, to afford access to the interior of the crank case, and at its top is provided with a suitably apertured and seated base plate 4, which may be integral with the remainder

35 of the crank case, if desired, and upon which seat and are rigidly secured the respective cylinders A, B, C, and D, which are rigidly secured in place thereon in the usual or any suitable manner.

40 Said cylinders, as shown, are each provided at the top with a relatively narrow and upwardly extending combustion chamber 5, which communicates with the top of the cylinder and extends substantially parallel to the crank shaft, and the top of the cylinder is so shaped as to afford a slight clearance above the piston when at the end of its exhaust, and its compression strokes.

Each of said cylinders is water jacketed,

50 and the water jacket may be afforded by coring the cylinder when cast or in any suitable manner. Conveniently, on the right or ignition side of said engine, a removable cover plate 6, affords one wall of the water jacket, and by removal permits access to the interior of the water jacket for inspection or repair.

55 For the remaining portion of the periphery of the cylinder, and extending well into the head thereof above and around the combustion chamber, the water jacket is preferably cored in the metal, as indicated by 7, and if desired, a cover plate 8, may be provided to afford access to the interior of the water jacket by its removal.

65 Inlet and exhaust ports of relatively

large size are provided at the left side of the combustion chamber and are closed by mechanically operated puppet valves 9, respectively, each of which is rigidly secured on stems 11, which extend through a suitable bearing sleeve 12, seated in a suitable bore in the side of the engine cylinder adjacent the combustion chamber, as shown in Figs. 4 and 7. Secured on the outer end of the valve stem 11, is a stop 13, between which and the wall of the cylinder engages a pushing spring 14, said spring acting at all times to hold its valve normally closed. As shown, an oil aperture is provided in the bearing sleeve 12, for each valve stem, and opens upwardly at the outer side of the cylinder, as indicated by 15, in Fig. 4, whereby the oil (converted practically to a vapor by the splash lubrication hereinafter described) finds access to the stem to lubricate the same at all times.

The inlet manifold X, indicated in dotted lines in Fig. 1, requires but two branches for a four cylinder engine, one of the branches opening directly to the inlet valves, 90 in the cylinders A and B, and the other of the same opening directly to the inlet valves, in the cylinders C and D, while the exhaust manifold Y, as indicated also in dotted lines in Fig. 1, is provided with four branches 95 which lead from the respective exhaust valves and upwardly therefrom.

The right side of the combustion chamber, or that opposite the valves, is bored to afford relatively large threaded openings therein, 100 one directly opposite each of the valves and threaded thereto are closures 16, for the exhaust valves, and 17, for the inlet valves, the latter of said closures being apertured to permit the insertion of a spark plug 105 therein. Said closures, upon removal, permit ready removal of the respective valves through the opening therefor, and permit the hand to be inserted into the cylinder to permit the cylinder to be thoroughly 110 cleaned and any carbon therein removed when desired, and without necessitating removing the cylinders from the crank case.

Connected with the respective cranks of the crank shaft, are connecting rods 20, of 115 course, one for each cylinder, and each engaged with a piston 21, which may be constructed in the usual or any suitable manner. The crank shaft is provided on its outer end with a gear wheel 22, which 120 meshes with a larger gear wheel 23, secured on a cam shaft 24, and affording a two to one drive therefor, said cam shaft being journaled in the crank case extending longitudinally at the rear side thereof, and 125 provided with suitable cams for actuating the respective valves. Said gears are, of course, incased to permit the same to run in oil.

130 Journaled above the cam shaft, is a tubu-

lar shaft 25, journaled on which are rocker arms 26, one for each inlet valve, and one for each exhaust valve, the upper, longer end of each of which extends into contact 5 with the outer end of the corresponding valve stem, as shown in Figs. 1 and 3, while the lower end thereof, which may be provided with a suitable anti-friction shoe 27, or roller extends into bearing against the 10 cam shaft in position to be contacted and actuated by the appropriate and corresponding cam thereon, so that when the shorter end of said lever is actuated by the cam, the upper end is thrown inwardly with 15 greater velocity, instantly affording full opening of the valve actuated thereby, which, upon release of said rocker arm by said cam, is instantly closed by the action of the valve spring 14.

20 The bearing on said tubular shaft 25, for the rocker arms, is supplied with force feed lubrication; so also is the lower end of said rocker arm, so that the friction occasioned by the contact of said rocker arms by the 25 respective cams, is reduced to a minimum. For this purpose, as shown, an oil compartment is provided in the bottom of the crank case, an inner floor or bottom 28, being provided therein, as shown in Figs. 3 and 6, the 30 space beneath said inner floor affording an oil well or container, and communicating therewith at the bottom, and bored in the side of the cylinder, is a casing 29, providing a cylindric bore or chamber therein in 35 open communication with said oil compartment at its inner side, as shown in Fig. 10. Said chamber is closed at its bottom by the threaded head 30, of a cylindric cage 31, which extends upwardly to suitable packing 40 at the top of said casing to afford a tight joint, as shown in Fig. 10.

Rigidly secured in said casing, and projecting upwardly through suitable webs 32 and 33, in the side of the crank case, is a 45 cylindric pump valve 34, which extends to near the lower end of the cylindric cage, and is there provided with an inlet passage closed by the upwardly opening ball valve 35, or other suitable valve 50 adapted to permit the inflow of the oil. Within said pump barrel is a reciprocating pump rod 36, which, at its lower end, fits closely in said barrel to afford the plunger, and is provided with an axial passage there- 55 in controlled by an inwardly opening ball valve 37, and, as shown, said pump rod 36, extends upwardly with its head 28, in position to be engaged by a cam 39, on the cam shaft, said cam acting to force the pump 60 rod downwardly. A spring 40, rests at one end on the web 33, and surrounds the pump barrel; and at its upper end engages the head 38, of the pump rod and acts to throw the pump rod upwardly affording the in- 65 take movement of the pump.

As shown, the inner passage in the plunger communicates in a chamber 41, above the plunger, and from which leads a pipe 42, which communicates in the bore of the tubular rocker arm shaft 25, so that the bore 70 of said shaft is at all times filled with oil. At each bearing of the rocker arm on said shaft, an oil port is provided which delivers the oil therethrough to the bearing for the rocker arm, as shown in Fig. 11, and connected in the hub of the rocker arm bearing, as shown in Figs. 3 and 11, is a pipe or tube 43, which leads downwardly therefrom along the inner face of the rocker arm and delivers oil therefrom to the shoe 27, or to 80 the end of the rocker arm contacted by the cam. Of course, the shoe 27, may be adjustably secured upon said rocker arm, and if desired adjusting means at the upper end 85 of the rocker arm may be provided to vary the bearing of said arm on the valve stem. Conveniently also, and particularly in the larger engines, an anti-friction roller may be provided on the lower end of the rocker to minimize friction from engagement of 90 the cam with the rocker for actuating the same. These, in engines of smaller size, are, however, not necessary.

Mechanism is provided for mechanically regulating the level of the oil in the crank 95 case. For this purpose, as shown in Figs. 2, 3, 5, 6, and 7, a tube 44, tubular except at its ends, is journaled in the crank case conveniently near the front side thereof, and is held in place by suitable bearings 45, in the 100 end of the crank case, and corresponding bearing 46, intermediate the ends thereof, said tube fitting closely in said bearings. Within the bearings 46, the tube is slotted peripherally for approximately a third of 105 the circumference, as indicated at 47, and directly beneath said tube an oil port 48, is provided through a floor 28, of the crank case.

On the outer end of the tube 44, is provided a crank arm 49, adapted to be manually actuated, and if preferred, may have connected therewith any suitable operating means whereby the same may be operated from the operator's seat, said operating 110 means, for example, leading to the dash of an automobile. By means of said lever, the amount of oil retained in the crank case may be varied at will, inasmuch as the height of the oil in the crank case will always be determined by the longitudinal slots 50, in 115 said tube, through which the oil flows at its level and thence through the peripheral slots or ports 47 and the ports 48, into the bottom oil compartment. Of course, when the 120 tube 44, is one of considerable diameter, a depth of oil may be maintained in the crank case when the slot 50, in the tube is turned upward, equal to the diameter of the tube, and a less depth of oil may be maintained 125 130

when the tube is rotated to bring said slots 50, near the floor or bottom of the crank case.

When the engine is assembled, and properly adjusted, a left side closing plate 51, is secured in place, as shown in Fig. 2, to entirely inclose the rocker shaft, rocker arms, and all the operating or moving parts of the engine, the joints, of course, being preferably gasketed or being ground down to afford a tight fit and prevent escape of oil.

The operation is as follows:

The left side of the crank case being open, the oil within the crank case is driven into a fine mist, almost vaporous in character, which at all times bathes all the operating parts of the engine, affording efficient lubrication. The oil falling upon the valve stem 11, and passing into the oil ports 15, in the sleeve 12, acts to cool and insures thorough lubrication of the valve stem. Oil is also splashed to lubricate the points of contact at the upper end of the rocker arm which contact with the ends of the valve stem. The bearings of the rocker arm on the rocker shaft, and the point of contact thereof with the cam, are also thoroughly lubricated by oil being splashed thereon.

Only very slight power is required for operating the oil pump, whereby the oil is kept in circulation from the oil well within the rocker shaft, and thence back into the bottom of the crank case for splash lubrication, whereby the crank shaft, piston and cylinder are at all times maintained satisfactorily lubricated. In actual operation, an engine embodying the construction herein described has been found by test to afford a large percentage of efficiency over engines of other construction. We ascribe this largely to the construction and arrangement of each cylinder and the location of the ignition device and the well lubricated and quick easy acting valve mechanism.

Of course, it is to be understood that details of construction will vary through a considerable degree with the size of the engine. For instance, if it is desired, rollers may be provided on the cam ends of the rocker arms for large engines and in some instances force feed lubrication may be used elsewhere than as shown and described.

We have, of course, shown but a preferred form of our invention, but we do not purpose limiting the patent granted otherwise than necessitated by the prior art.

I claim as my invention:

1. In a lubricating system, the combination of an engine having a crank case and crank shaft therein, an oil receptacle in the crank case from which oil is splashed by the operation of the crank shaft for lubricating the bearings thereof, and a tube extending lengthwise of the crank case and rotatable to control outlets therethrough from the oil receptacle to regulate the level of oil in said receptacle.

2. In a lubricating system, the combination of an engine having a crank case and crank shaft therein, an oil receptacle in the crank case from which oil is splashed by the operation of the crank shaft for lubricating the bearings thereof, a rotatable tube extending lengthwise of the crank case through the oil receptacle and slotted longitudinally, and bearings communicating with the interior of said tube and opening downwardly to provide a discharge for the oil in said tube.

In witness whereof we have hereunto subscribed our names in the presence of two subscribing witnesses.

FREDERICK S. DUESENBERG.
AUGUST S. DUESENBERG.
